UNITED STATES PATENT OFFICE.

CLAYTON L. ROLOSON, OF BUFFALO, NEW YORK, ASSIGNOR TO CURTISS AEROPLANE AND MOTOR CORPORATION, OF BUFFALO, NEW YORK, A CORPORATION OF NEW YORK.

ENGINE-BED SUPPORT.

1,382,387.

Specification of Letters Patent. Patented June 21, 1921.

Application filed January 30, 1919. Serial No. 274,023.

To all whom it may concern:

Be it known that I, CLAYTON L. ROLOSON, a citizen of the United States, residing at Buffalo, in the county of Erie and State of 5 New York, have invented certain new and useful Improvements in Engine-Bed Supports, of which the following is a specification.

My invention relates to airplanes and more particularly to an improved engine bed support. The support comprises (preferably) a substantially V-strut in which the legs of the V diverge continuously upwardly to points beyond the horizontal plane of the 10 engine bed. In one embodiment of the invention the V-strut is erected upon the lower or one of the lower supporting surfaces and is continued to and beyond the engine bed for connection with another or upper supporting surface to provide a strut connection between the two. This construction and arrangement is advantageous in that the motor or power plant may be projected beyond and between the legs of the V-strut without interference. The continued divergence of the 15 legs of the strut beyond the horizontal plane of the engine bed admits of such an arrangement. In order however to retain the much desired triangular bracing in connection with the V-strut a cross brace is provided and located at a point above the engine bed preferably in the vicinity of the point of maximum divergence of the strut legs. This 20 brace not only offers a cross connection between the legs of the V-strut but it serves in addition as a line of demarcation between the two triangular strut sections which together constitute the engine bed support or wing post frame. Above the cross brace the legs of the support converge sharply and connect with a supporting surface thereabove. This connection, in the embodiment illustrated lies directly above the common connection at the foot or apex of the V. The invention, however, consists in the novel features and combination of parts herein disclosed, although the invention is more particularly pointed out in the claims.

Of the drawings:

Figure 1 is a side elevation of an aeronautical motor together with its support, the support being constructed according to and illustrative of my invention;

Fig. 2 is a front end elevation of the support; and

Fig. 3 is a rear end elevation of a different though related V-strut used in connection with and forming a part of the engine bed mounting.

The invention as illustrated comprises an 60 engine bed 10, the beams 11 of which extend in a fore and aft direction and parallel. Said beams or rather the engine bed is located between the supporting surfaces of the machine.

At its forward end the engine bed 10 is supported in its horizontal position by a substantially V-strut 12. The V-strut is erected upon the front wing beam 13 of the lower supporting surface or wing. It comprises upwardly divergent legs 14, the lower pairs of which directly engage and support the engine bed beams 11 from beneath. Lap joint fittings 15 are used as a means for fastening the strut legs 14 to the engine bed 75 beams.

That portion of the V-strut 12 beneath the engine bed 10 is preferably constructed of wood. Said legs 12 however do not terminate at the engine bed. Instead there is 80 provided a metal V-strut section 16 having its legs 17 in line with the legs 14 of the lower or wooden section of the V-strut 12. Said metal V-strut, or rather the legs thereof, diverge continuously upwardly to 85 points above the engine bed, the point of maximum divergence being nearer the upper supporting surface than the lower supporting surface. The point of maximum divergence is designated as 18. From said point 90 18 the legs of the metal strut section converge sharply upwardly as indicated at 19 for connection with said upper wing or supporting surface. The point of connection between the legs 17 of the metal section of the 95 V-strut with the upper wing lies directly above the point of connection of the legs 14 of the wooden strut section with the lower wing (see Fig. 2). At or near the maximum point of divergence of the V-strut legs 100 a cross brace 20 between the legs 17 of the metal strut section 16 is provided. Its function is to prevent spreading of the V-strut legs. It further serves as a line of demarcation between that portion of the strut or 105 wing post frame which is characterized by divergence upwardly and that portion which is reversely characterized. Both portions, it will be noted, partake of the much desired triangular form.

In view of the fact that the V-strut legs diverge continuously to a point above the horizontal plane of the engine bed it is possible to locate the engine or motor 21 between them without interference. This 5 location of the motor between the legs of the V-strut centers it (the motor) more nearly over the lower section of the V-strut and admits of the projection of the forward 10 end of the motor out beyond the transverse vertical plane of the leading edges of the wings. Were the motor confined to the space to the rear of the V-strut 12 obviously a connection of some kind would be required 15 between the motor and the propeller in order that the field of operation of the latter might lie in advance of the wings.

The foregoing description has references 20 more particularly to the use of the support in connection with machines of the tractor type. The invention however is not thus limited. It may equally as well be used in connection with machines of the pusher type. To so use the invention it is but 25 necessary to construct the support at the rear end of the engine bed in the manner above described allowing the motor to project between the strut legs rearwardly beyond the engine bed.

30 The support for the rear end of the engine bed herein illustrated is of a more or less conventional design. The supporting portion of the strut designated as 22 is of the usual V-form while the continuing portion of the strut *i. e.*, that portion above the engine bed is of inverted V-form, the strut sections together constituting a substantially diamond shaped strut or a triangulated wing post frame. The upper or continuing 35 portion of the rear strut is indicated in the drawings at 23. Said upper section connects with the rear wing beam 24 of the upper wing and the lower section with the rear wing beam 25 of the lower wing. It might 40 be noted here also that the upper section of the forward wing post frame connects directly with the front wing beam 26 of the upper wing.

Usually an engine bed support of the 45 character disclosed is used in connection with a twin or multi motored machine, though not necessarily. In the embodiment of the invention selected for illustration two engine bed supports are provided. These 50 supports are arranged symmetrically at opposite sides of the fore and aft axis of the machine, each support affording a connection between the superposed supporting surfaces—hence the designation wing post 55 frames. Only one complete support however is illustrated in the drawings, though it is to be understood that the support at the opposite side of the machine is to be of a duplicate construction. It is to be 60 understood further that the rear portions 65

of the engine bed support may be interchanged with the forward portions as above explained to accommodate the motor regardless of its location. Or, if desired, the character of wing post frame illustrated in Fig. 2 of the drawings may be duplicated at both the front end and the rear end of the engine bed, though such a construction is not necessary unless the engine beds are designed to support two separate motors driving respectively a tractor and a pusher propeller.

The wing post frames and consequently the engine section of the craft may or may not be braced in the manner indicated although the bracing shown in Figs. 1 and 2 is preferred by reason of the assured clearance at all points. Said bracing comprises a single cable 27 which extends back from the forward wing beam 26 of the upper wing directly over the motor to a point 28; from which point branch cables 29 diverge downwardly for connection with the rear ends of the two engine bed beams. There is provided in addition a cable 30 which connects with the rear wing beam 24 of the upper wing at one end and with the cables 27 and 29 at the point 28 at its opposite end. This cable 30 tends to strengthen the connection between the engine bed and the upper wing. Beneath the engine bed the wing post frame is braced in a fore and aft direction by cross arranged cables 31 and 32. The cable 31 interconnects the forward end of the engine bed with the rear wing beam 25 of the lower wing while the cable 32 interconnects the rear end of the engine bed with the forward wing beam 13 of the lower wing. Cable 31 should be extra heavy as it enters into and forms a part of the draft system of the machine.

In conclusion it may be noted that the wing post frame or engine bed mounting may be used in connection with machines other than biplanes and that the ends of the wing post frames may connect with wings other than the upper and lower wings of the machine.

While I have described my invention in detail in its present preferred embodiment, it will be obvious to those skilled in the art after understanding my invention, that various changes and modifications may be made therein without departing from the spirit or scope thereof. I aim in the appended claims to cover all such modifications and changes.

What is claimed is:

1. In an airplane, a wing structure including superposed supporting surfaces, an engine bed mounted between the supporting surfaces, a support for the engine bed including a V-type strut having its legs continuously upwardly divergent beyond the horizontal plane of the engine bed, the

V-strut being erected upon one of the supporting surfaces, and a motor mounted on the engine bed and extended horizontally between and beyond the upwardly divergent 5 legs of the strut.

2. In an airplane, a wing structure including superposed supporting surfaces, an engine bed mounted between the supporting surfaces, a support for the engine bed including 10 a V-type strut having its legs arranged to diverge upwardly to a point beyond the horizontal plane of the engine bed, the V-strut being erected upon one of the supporting surfaces and connected with another 15 of the supporting surfaces to provide a strut connection between the two, and a motor mounted on the engine bed and extended horizontally between and beyond the upwardly divergent legs of the strut.

20 3. In an airplane, the combination with a motor, of a wing structure including superposed supporting surfaces, an engine bed mounted between the supporting surfaces, and a support for the engine bed including 25 a V-type strut having its legs continuously divergent beyond the horizontal plane of the engine bed, and a motor mounted on the engine bed and extended horizontally between and beyond the upwardly divergent 30 legs of the strut.

4. In an airplane, the combination with a motor, of a wing structure including superposed supporting surfaces, an engine bed mounted between the supporting surfaces, a 35 V-type strut mounted upon one of the supporting surfaces to support the engine bed from beneath, the legs of the V-strut being continued beyond the horizontal plane of the engine bed substantially in alignment with 40 such portions of the V-strut as support the engine bed from beneath, and a motor mounted on the engine bed and extended horizontally between and beyond such portions of the legs of the V-strut as extend 45 above the engine bed.

5. In an airplane, a wing structure including superposed supporting surfaces, an engine bed mounted between the supporting surfaces, a motor and a support for the engine bed including 50 a V-type strut having its legs extended divergently upwardly from one of the supporting surfaces beneath the engine bed to points above the engine bed

and thence extended convergently upwardly to one of the supporting surfaces above the 55 engine bed, the divergence of the strut legs upwardly beyond the engine bed being sufficiently acute and sufficiently prolonged to clear the opposite sides of the motor.

6. In an airplane, a wing structure including superposed supporting surfaces, an engine bed mounted between the supporting surfaces, a support for the engine bed including a V-type strut having its legs continuously upwardly divergent beyond the 65 horizontal plane of the engine bed, a motor mounted on the engine bed and extended horizontally between and beyond the upwardly divergent legs of the strut, and a cross brace between the legs of the V-strut 70 disposed above the motor.

7. In an airplane, the combination with a motor, a wing structure including superposed supporting surfaces, an engine bed mounted between the supporting surfaces, a support for the engine bed including a V-type strut having its legs continuously upwardly divergent beyond the horizontal plane of the engine bed, a motor mounted on the engine bed and extended horizontally 75 between and beyond the upwardly divergent legs of the strut, and a cross brace between the legs of the V-strut extended across and over the motor.

8. In an airplane, the combination of a 85 motor, superposed supporting surfaces, an engine bed mounted between the supporting surfaces, and a combined wing post frame and support for the engine bed including a V-type strut having its legs continuously upwardly divergent from a common point on the lower supporting surface to and beyond the engine bed, the legs of the V-strut at points above the motor being in-bent to converge sharply and connect at a common 90 point with the upper supporting surface, the point of commencement of the upward convergence of the V-strut legs being sufficiently removed from the engine bed and from the motor to admit of the latter being disposed 95 between the legs of the strut without interference.

In testimony whereof I hereunto affix my signature.

CLAYTON L. ROLOSON.
